DESIGN.

W. WOOD.

DECORATIVE PATTERN FOR DISHES.

No. 16,043.

Patented Apr. 14, 1885.

UNITED STATES PATENT OFFICE.

WILLIAM WOOD, OF LAWRENCE, MERCER COUNTY, ASSIGNOR TO SPENCER M. ALPAUGH AND FRANK A. MAGOWAN, OF TRENTON, NEW JERSEY.

DESIGN FOR A DECORATIVE PATTERN FOR DISHES.

SPECIFICATION forming part of Design No. 16,043, dated April 14, 1885.

Application filed November 22, 1884. Term of patent 3½ years.

To all whom it may concern:

Be it known that I, WILLIAM WOOD, a citizen of the United States, residing in the township of Lawrence, in the county of Mercer and State of New Jersey, have invented and produced a new and original Design for Dishes, of which the following is a specification, reference being had to the accompanying photographic illustration, forming part thereof.

The design consists of a landscape or other view, A, in the lower right-hand corner of the illustration, which view may be varied to suit the taste. The view A is framed off and separated from the rest of the ornamentation by the bar or angular bracket B, representing an unrolled scroll, and bearing a row of half-rosettes. The upper end of the scroll is rolled around a sprig, which frames one side of the inclosed landscape, while the lower and left-hand end of the bracket is foliated. Framing the lower part of the landscape, and passing under the bracket B and branching out across the dish, is the sprig C, bearing flowers and leaves, while another branch of the sprig

passes up through the bracket and across the upper part of the design, and bends toward the end of the other branch of the sprig. Perched upon the ends of the branches are birds facing toward each other, and between them is a flying bee.

The principal features of my design are the ornamental bracket B and the combination of the bracket B and the landscape or other view and twigs.

What I claim is—

The design for a dish, consisting of the decorative landscape in the corner of the design, and separated from the rest of the figure by an ornamental bracket or bar, the rest of the figure being composed of branches or twigs, with leaves and flowers, and birds perched upon the branches, substantially as described and shown.

WILLIAM WOOD.
